SPOON OR SIMILAR ARTICLE

William S. Warren, Meriden, Conn., assignor to R. Wallace & Sons Manufacturing Company, Wallingford, Conn., a corporation of Connecticut

Application July 13, 1955, Serial No. 36,965

Term of patent 14 years

(Cl. D54—12)

FIG. 1

FIG. 4

FIG. 5

FIG. 2

FIG. 3

FIG. 6

Fig. 1 is a front elevational view of a spoon showing my new design;

Fig. 2 is a side elevational view thereof;

Fig. 3 is a rear view thereof;

Fig. 4 is a sectional view taken on line 4—4 of Fig. 1;

Fig. 5 is a sectional view taken on line 5—5 of Fig. 1; and

Fig. 6 is an enlarged view of the floral like decoration shown in Fig. 1.

I claim:

The ornamental design for a spoon or similar article, substantially as shown.
